CLAIM

The ornamental design for a sacroiliac belt, as shown and described.

DESCRIPTION

FIG. 1 is a perspective view of a sacroiliac belt design showing my new design.

FIG. 2 is a front view of a sacroiliac belt.

FIG. 3 is a rear view of a sacroiliac belt.

FIG. 4 is a left side view of a sacroiliac belt.

FIG. 5 is a right side view of a sacroiliac belt.

FIG. 6 is an enlarged top view of a sacroiliac belt.

FIG. 7 is an enlarged bottom view of a sacroiliac belt; and, FIG. 8 is perspective view of a sacroiliac belt design showing in a state of use.

The raised strap features on the outer surface of the sacroiliac belt shown in broken lines in FIGS. 1, 2, and 4 through 8, are portions of the sacroiliac belt that form no part of the claimed design. The remaining portions of the drawings shown in broken lines represent stitching, which does form a part of the claimed design.
